Primary Examiner — Keli L Hill*Assistant Examiner* — Harold E Blackwell, II(74) *Attorney, Agent, or Firm* — GRUMBLES LAW PLLC; Brittany Haanan(57) **CLAIM**

The ornamental design for a wall mount, as shown and described.

DESCRIPTION

FIG. 1 is a front view of a wall mount showing our new design;

FIG. 2 is a back view of the wall mount;

FIG. 3 is a perspective front view of the wall mount;

FIG. 4 is a perspective back view of the wall mount;

FIG. 5 is a perspective front view of the wall mount; and,

FIG. 6 is a perspective back view of the wall mount.

The broken lines depict parts of the wall mount that form no part of the claimed design.

1 Claim, 3 Drawing Sheets---
